UNITED STATES PATENT OFFICE.

FREDERICK K. WRIGHT, CHARLES W. GAGE, AND WILLIAM F. HITCHCOCK,
OF HOMER, NEW YORK.

POSITIVE SHUTTLE-MOTION FOR LOOMS.

SPECIFICATION forming part of Letters Patent No. 320,902, dated June 23, 1885.

Application filed September 29, 1883. (No model.)

To all whom it may concern:

Be it known that we, FREDERICK K. WRIGHT, CHARLES W. GAGE, and WILLIAM F. HITCHCOCK, citizens of the United States, 5 residing at Homer, in the county of Cortland and State of New York, have invented certain new and useful Improvements in Positive Shuttle-Motions for Looms; and we do hereby declare the following to be a full, clear, and 10 exact description of the invention, such as will enable others skilled in the art to which it appertains to make and use the same.

Our invention is an improvement in positive shuttle motions such as are employed in looms 15 for weaving wire and other cloth.

It consists, chiefly, of a pair of picker-staffs for moving the shuttle-carriers, which are united to the said shuttle-carriers by ribbons, 20 said staffs being moved laterally by means of levers pivoted on a bracket secured to the beam of the lay or beater, connecting arms or rods between the said levers and picker-staffs, bars provided with cam-grooves fixed to the loom-frame, and arms or rods guided upon 25 the lay-frame, connected with said levers, and provided with projections or rollers fitting into said cam-grooves, all of which will be set forth hereinafter.

In the drawings, Figure 1 is a sectional view 30 of a portion of a loom, showing the shuttle-motion in elevation. Fig. 2 is a plan view showing the shuttle-operating mechanism. Figs. 3 and 4 show details of parts hereinafter described.

Referring to the drawings, A is the beam of the lay, provided at each end with plates *a a*, formed into loops *a'*, which latter serve as guides for the shuttle-carriers *B B'*, and the curved rocker-arms *F F'* of the picker- 40 staffs *D D'*. The carriers *B B'* have longitudinal grooves *d d* on both sides, into which the tongues or projections *e e* on the opposing faces of the plates *a* and loops *a'* extend, and serve as accurate guides for the carriers.

To the ends of the shaft C, which forms the 45 axis of motion of the lay, are pivoted on suitable clips or clasps, *b b*, the picker-staffs *D D'*, for operating the shuttle-carriers. Ribbons *f f'* are secured adjustably at opposite ends to the 50 heels of the rocker-arms *F F'* and the inner

ends of the carriers, respectively, while similar ribbons, *f' f''*, are secured adjustably to the toes of said rocker-arms and the outer ends of the carriers, respectively. The rocker-arms *F F'* are united to the tops of the picker-staffs, 55 near the heels of the arms, so as to permit the said arms to reach inward across the machine to as great an extent as possible.

G is a bracket secured to the beam *A* of the lay, which serves as a bearing to a shaft which 60 forms the fulcrum of shear-levers *H H'*. To opposite ends of said levers are pivoted arms *I I'* and rods *K K'*. The picker-staffs *D D'* have pivoted in the slots *c* the rods *K K'*, which latter may be adjusted in the said slots by any 65 well-known and suitable means, to change the throw of the picker-staffs to suit circumstances. To the ends of the arms *I I'*, upon suitable pins, are secured anti-friction rollers *g g'*. Plates *J J'*, grooved on their under edges, are 70 secured to the lay-beam *A*, and these plates, together with short extensions *j'* on the arms *I I'*, serve as guides to the latter as they are moved back and forth.

L L' are bars formed with cam-grooves, which 75 are U-shaped in vertical transverse section, and have the general conformation shown in the drawings, said bars being permanently fixed to the upper horizontal beams of the loom-frame and braced together by a rod, *h*. The 80 grooved bars *L L'* form races for the movement of the anti-friction rollers *g g'*, and during the reciprocating or swinging movement of the lay the carriers *B B'* receive the proper movement through arms *I I'*, levers *H H'*, rods *K K'*, picker-staffs *D D'*, and the ribbons uniting the rocker-arms *F F'* with said carriers.

Motion is given to the lay in the usual manner by cranks *A''* on the main shaft *A'* of the loom, and rods *A'''*, connecting the lay with 90 such cranks, and, as previously implied, the movement of the mechanism composing the shuttle-motion described is coincident with the movement of the said lay.

The shuttles to be used with our shuttle-motion are such as are adapted for use with carriers that alternately take hold of and release the same automatically—such, for instance, as is shown and described in the patent to F. K. Wright, No. 299,610, June 3, 1884. 95

The bars in which the cam-grooves are formed are so shaped that when motion is imparted to the carriers a slow impulse is given at starting, which is quickened at the center of the stroke, and then retarded, so that the liability to concussion at the moment of change of the shuttle from one carrier to the other is obviated.

In Fig. 4 of the drawings we show the end of the rocker-arm F' with a lug secured thereon, and the ribbon f³ provided with a screw-threaded end and a nut, f⁴. Said arrangement is for the purpose of tightening or loosening said ribbon as it is lengthened or shortened from any cause. A similar arrangement may be applied to the outer ends of the carriers B B', as indicated in Fig. 1.

Having thus described our invention, what we desire to claim and secure by Letters Patent is—

1. The combination of the lay, the carriers, the flexible ribbons f f² f' f³, the rocker-arms F F', connected to the carriers by said ribbons, the picker-staffs D D', united to the rocker-arms near the heels of said arms, and the cam-grooved bars L L', with shear-levers H H', the connecting-arms I I', secured at their inner ends to the tops of the levers H H', and at their outer ends being provided with the rollers g to enter the cam-grooves, and the connecting-rods K K', connected at their inner ends to the lower limbs of the levers H H' and at their outer ends to the picker-staffs, and means for operating the lay, as and for the purpose set forth.

at their outer ends to the picker-staffs, and means for operating the lay, substantially as and for the purpose specified.

2. The combination of the lay, the carriers, 35 the picker-staffs, means for connecting the carriers and the picker-staffs, and the cam-grooved bars L L', with the shear-levers H H', the connecting-arms I I', secured at their inner ends to the tops of the levers H H', and at 40 their outer ends being provided with rollers g to enter the cam-grooves, and connecting-rods K K', connected at their inner ends to the lower limbs of the levers H H' and at their outer ends to the picker-staffs, and means for operating the lay, as and for the purpose set forth. 45

3. The combination, with the frame and cam-grooved bars fixed thereto, of the lay, the shuttle-carriers, the picker-staffs, ribbons connecting the carriers and picker-staffs, and 50 levers and rods, substantially as described, for imparting motion to said picker-staffs from the said cam-grooves as the lay vibrates, as and for the purpose set forth.

In testimony whereof we affix our signatures 55 in presence of two witnesses.

F. K. WRIGHT.

CHARLES W. GAGE.

WM. F. HITCHCOCK.
